WRAP MECHANISM

Oscar Fregeolle, Central Falls, R. I., assignor to
Hemphill Company, Central Falls, R. I., a corporation of Massachusetts

Application April 9, 1946, Serial No. 660,790

6 Claims. (Cl. 66—135)

1

This application is a continuation in part of U. S. application No. 559,136, filed October 18, 1944.

This invention relates to an improvement in circular, independent needle knitting machines of the superposed, co-axial cylinder type and, in particular, to wrap mechanisms for such machines in which are included a spindle adapted to be positioned both eccentrically and concentrically of the cylinders and a wrap horn. A machine of this character is described in co-pending application #559,136, filed October 18, 1944. By this invention means is provided for moving the wrap horn into and out of operating position through the motion of the wrap spindle 15 from concentric to eccentric position and vice versa. One form of the invention is shown in the drawings of which:

Fig. 1 is a view partly in section of a part of a knitting machine of the type referred to, illustrating in particular the operative and inoperative positions of the wrap horn and the means by which it is moved from one position to the other;

Fig. 2 is a view of a part of the wrap horn operating mechanism as positioned when the wrap spindle is moving into its eccentric wrapping position and the wrap horn in its operating position;

Fig. 3 is a plan view of a part of Fig. 1 showing the position of certain parts when the wrap spindle is in its concentric position and the wrap horn inoperative; and

Fig. 4 is an elevation of the parts shown in Fig. 3 and representing the same conditions.

In two cylinder machines of the above type and as described in the co-pending application referred to, the wrap spindle, when inoperative, is positioned substantially in the center of the cylinder, i. e., concentric therewith. To wrap, this spindle is swung from this central position until its wrapping head overlaps the needle circle above the needles of the lower cylinder in the manner well known in connection with single cylinder machines.

Also, as is well known in relation to single cylinder machines, a wrap horn is used under which the wrap yarn passes on its way from the wrapping head to the needles selected for wrapping to be guided and maintained at the proper heights for the wrapping operation.

In Fig. 1 of the drawings, the lower and upper cylinders are shown at 1 and 2 respectively. The wrap spindle 3 projects through the upper cylinder and terminates at its lower end in a wrap-

2

ping head (not shown), the elevation of which is that suitable for wrapping selected needles working in the lower cylinder. The associated wrap horn 4 is shown in its inoperative position by solid line and in its operating position by dot and dash line at 4'. This horn may be of any desired contour, that shown being the improved type described and claimed in co-pending application #607,300, filed July 27, 1945.

This invention relates to the mechanism whereby the wrap horn is moved from its inoperative to its operative position and vice versa automatically and in time with the movement of the wrap spindle to and from its inoperative and operative positions.

As shown in Fig. 1, wrap horn 4 is mounted at one end on a shaft 5 which is rigidly held at its upper end by plate 6. Plate 6 is fastened to another plate 7 in such a way that it is longitudinally adjustable. Plate 7 is rigidly mounted on the top of a shaft 8 which is longitudinally slidable in a sleeve 9 and is urged towards its lowermost position by a spring 10.

In Fig. 1 shaft 8 is shown in full line in its up position and wrap horn 4 is also shown in full line in its up or inoperative position. The down position of shaft 8 is indicated at dotted line at 8' and the corresponding down or operative position of wrap horn 4 is indicated in dot and dash line at 4'.

The outer end 11 of plate 7 moves in a slot 12 of plate 13 whereby it is held in longitudinal alignment. Associated with the outer end 11 of plate 7 is a bell crank 14, the lower end 15 of which underlies plate 7 as best shown in Figs. 1, 2 and 4. If the upper arm 16 of bell crank 14 is rocked so that its lower arm 15 is raised, as shown in Fig. 4, plates 7 and 6 and shaft 5 will be raised to move wrap horn 4 into the inoperative position shown in full line in Fig. 1. If bell crank 14 is permitted to rock in the other direction so that its arm 15 swings downward, plate 7 and 6 and shaft 5 will lower wrap horn 4 into its operative position shown in dot and dash line at 4' in Fig. 1. Spring 10 will insure that shaft 8, which is the support for these elements, will move down to the extent permitted by slot 12 through which plate 7 extends.

Bell crank 14 is operated as just described by the means which supports the wrap spindle and which moves the wrap spindle between its concentric and eccentric position. This consists of a substantially annular plate 18 swingably mounted at one side 19 and which is supported, preferably, by a ball bearing 20. Plate 18 sup-

ports a gear (not shown) by means of which the wrap spindle is driven and which is keyed to the wrap spindle. For further details of this arrangement reference may be had to co-pending application #559,136.

The other side of plate 18 is provided with an extension or arcuate portion 21 on which is mounted a roller 22. Roller 22 runs upon a track 23 best shown in Figs. 3 and 4 which thus serves as the support for this side of plate 18. Because of ball bearing 20 and roller 22 plate 18 and the wrap spindle assembly can swing freely upon the ball bearing as a pivot along track 23. The means for swinging plate 18 as described is indicated at 24. It can take any suitable form. Track 23 is provided with adjusting nuts 25 and 26 by means of which the limit of swing of plate 18 in each direction can be established.

Extending outwardly from arcuate portion 21 is a pin 27 adapted to engage with the inside edge of arm 16 of bell crank 14. The arrangement is such that when plate 18 is swung in the direction to position wrap spindle 3 concentrically of the cylinder pin 27 will engage arm 16 of bell crank 14 to rock it in the same direction and to thereby raise the other arm 15 of bell crank 14 and, through the connections described, raise the wrap horn 4 into its up inoperative position. When plate 18 is swung the other way to move the warp spindle into its eccentric operating position pin 27 will tend to leave arm 16 which, consequently, permit shaft 8 to drop through inertia and the effect of spring 10, so that the wrap horn is lowered into its operative position.

It is essential that the wrap horn shall be in operative position before the wrap spindle reaches its operative position. Consequently, the parts are so arranged that bell crank 14 will operate to lower the wrap horn during the first part of the swing of plate 18 after which plate 18 continues to swing until wrap spindle 3 is established in its operative position, pin 27 leaving arm 16 during this part of the swing. This is illustrated in Fig. 2 in which it will be noted that plate 7 and, consequently, the wrap horn has been fully lowered when roller 22 reaches the full line position shown in Fig. 2. The final position of roller 22 at the end of the swing of plate 18 in this direction is shown in dot and dash line at 22'. From this it follows that, when plate 18 swings in the other direction to transfer wrap spindle 3 from its operative to its inoperative position, the initial part of this swing will not affect the position of the wrap horn which will remain in its operative position until pin 27 again strikes arm 16 of bell crank 14 and swings it backward so that plate 7 is lifted by the upswing of arm 15. That is to say, the horn is not raised until the wrap spindle has been swung out of the way. The resulting position of bell crank 14 and plate 7 is shown in Fig. 4.

I claim:

1. For a circular, independent needle, knitting machine having a wrap spindle and wrap horn, the combination of a support for said spindle adapted to be swung between a position in which the spindle is eccentric to the needle circle and a position in which said spindle is substantially concentric with the needle circle and means operated by said support for moving said wrap horn into inoperative position when said support is swung to move said spindle into its concentric

position and for causing said wrap horn to be moved into operating position when said support is swung to move said spindle into its eccentric position.

2. For a circular, independent needle, knitting machine having a wrap spindle and wrap horn, the combination of a support for said spindle adapted to be swung between a position in which the spindle is eccentric to the needle circle and a position in which said spindle is substantially concentric with the needle circle and means operated by said support for raising said wrap horn into inoperative position when said support is swung to move said spindle into its concentric position and for causing said wrap horn to be lowered into operating position when said support is swung to move said spindle into its eccentric position.

3. For a circular, independent needle, knitting machine having a wrap spindle and wrap horn, the combination of a support for said spindle adapted to be swung between a position in which the spindle is eccentric to the needle circle and a position in which said spindle is substantially concentric with the needle circle and means operated by said support for raising said wrap horn into inoperative position during the final stage of the swinging of said spindle towards its concentric position and for causing said wrap horn to be lowered into operating position during the initial stage of the swinging of said spindle to its eccentric position by said support.

4. For a circular, independent needle, knitting machine having a wrap spindle and wrap horn positive means for raising said wrap horn from a low to a high position, resilient means for returning said wrap horn to said low position, swingable means for controlling said wrap horn raising and lowering means, said swingable means also being the means whereby the wrap spindle is moved to and from a position substantially concentric with the needle circle.

5. For a circular, independent needle, knitting machine of the superposed co-axial cylinder type having a wrap spindle and a wrap horn, the combination of a support for said spindle adapted to be swung between a position in which the spindle is eccentric to the needle circle and a position in which said spindle is substantially concentric with the needle circle and means operated by said support for moving said wrap horn into inoperative position when said support is swung to move said spindle into its concentric position and for causing said wrap horn to be moved into operating position when said support is swung to move said spindle into its eccentric position.

6. For a circular, independent needle, knitting machine of the superposed co-axial cylinder type having a wrap spindle and a wrap horn, the combination of a support for said spindle adapted to be swung between a position in which the spindle is eccentric to the needle circle and a position in which said spindle is substantially concentric with the needle circle and means operated by said support for raising said wrap horn into inoperative position during the final stage of the swinging of said spindle towards its concentric position and for causing said wrap horn to be lowered into operating position during the initial stage of the swinging of said spindle to its eccentric position by said support.

OSCAR FREGEOLLE.
